FRINGED RUG

Clarence F. Arnold, Drexel Hill, Pa.

Application April 23, 1936, Serial No. 75,918

2 Claims. (Cl. 28—1)

This invention has to do with the art of rug manufacture, and is concerned primarily with the attachment of a fringe around the peripheral edge of a rug.

5 The practice of availing of a base cord as a mounting for a plurality of strands which, together, define a fringe, and attaching this base cord to the edge of a rug, is now known, but rugs made in accordance with the present day practice in this art present certain disadvantageous features which are intended to be overcome by the present invention.

10 These undesirable conditions may be attributed directly to the fact that the base cord which carries the fringe is attached to the rug proper by an overlapped joint which does not permit of the rug to lie smooth on the floor, and at the same time present a smooth, even surface.

15 With the foregoing conditions in mind, this invention has in view, as one of its important objectives, the provision of a rug, to the peripheral edge of which is attached a base cord carrying a fringe, and which base cord is in abutting relation to the edge of the main body portion of the rug.

20 In carrying out this idea in a practical embodiment, it is noted that the invention is particularly adaptable for use in conjunction with rugs of the so-called braided type, in which a braid is wrapped about itself to define a spiral, the edges of adjacent coils being joined together by interstitching.

25 In accordance with this invention, the base cord carrying the fringe is of substantially the same diametrical dimension as one of the braids making up the body portion of the rug, and this cord is attached to the braid defining the outer peripheral edge by the same stitching which joins the several braids of the rug body together.

30 Another important object of the present invention is to provide a novel method of assembling a rug fringe with the main body portion of a rug, and which method is characterized by the placing of the base cord carrying the fringe in abutting relationship with the peripheral edge of the rug, and fastening the said cord thereto.

35 Yet another object of the present invention is to provide a novel method of manufacturing a rug fringe. This invention proposes joining the strands which define the fringe proper to the base cord which carries the same, by the use of knitting operations, as carried out in the ordinary well-known flat knitting machine.

40 In carrying out this thought in actual practice,

a pair of base cords are fed to a conventional flat knitting machine as is the strand which makes up the fringe. One set of needles on the knitting machine takes the fringe strand as it is formed into loops with each bend thereof adjacent to and engaging one of the base cords, while the other set of knitting needles stitches the fringe strand to the respective base cords at the loops of the fringe strand.

45 The final step in the process of fringe manufacture lies in cutting the various loops of the fringe strand along a line intermediate the two base cords to provide two individual pieces of rug fringe.

50 Various other more detailed objects and advantages will in part become apparent and in part be hereinafter stated as the description of the invention proceeds.

55 The invention, therefore, comprises the combination of a rug and fringe in which the fringe is joined to the rug by a butt joint between the base cord of the fringe and rug. The method of assembling the fringe with the rug also constitutes a part of the invention, as well as the method of manufacturing the fringe itself.

60 For a full and more complete understanding of the invention, reference may be had to the following description and accompanying drawings, wherein:

65 Figure 1 is a side view in elevation of a piece of rug fringe made in accordance with the precepts of this invention.

70 Figure 2 is a view similar to Figure 1, showing the opposite face of the fringe.

75 Figure 3 is a transverse section taken through the fringe about on a plane represented by the line 3—3 of Figure 1.

80 Figure 4 is a plan view showing a piece of the fringe as it is attached to a rug.

85 Figure 5 is a plan view, somewhat diagrammatically bringing out the process of manufacturing the fringe, and.

90 Figure 6 is an enlarged detail section taken about on the plane represented by the line 6—6 of Figure 4.

95 Referring now to the drawings, wherein like reference characters denote corresponding parts, and particularly Figure 4, a rug is there illustrated and referred to generally by the reference character R. As shown in Figures 4 and 6, the rug R is made up of a braid 10 which is wound about itself in a spiral-like form. Where the edges of one turn of the braid 10 engage the adjacent edge of another braid, the engaging edges are joined together by interstitching which 100

is designated 11, this process of rug manufacture being now common knowledge.

At this point it might be well to note that, while the invention is herein illustrated and described as the application of a fringe to a rug of the braided type, the invention is not to be limited to this particular type of rug, as the invention is also susceptible for use in conjunction with any of the woven rugs.

10 The outer peripheral edge of the main body portion of the rug R is defined by the outermost turn of the braid 10, which is herein designated 12, and the rug fringe, referred to as F, is attached to this turn 12 in a manner to be herein-15 after described.

Referring now more particularly to Figures 1, 2, and 3, the fringe F is shown as comprising a base cord 13 which, preferably, is of the twisted construction well-known in the textile art, and 20 to which base cord 13 are attached fringe strands 14, the attachment between the fringe strands 14 and base cord 13 being shown as taking the form of the stitches shown at 15. It is notable that each fringe strand 14 is integrally connected with 25 another fringe strand by a bend, referred to as 16.

In assembling the fringe F with the rug R, the base cord 13 is placed in abutting engagement with the outer peripheral edge of the turn 12, and 30 stitched thereto by interstitching designated 17, which may be substantially identical with the interstitching at 11, which joins the several turns of the braid 10 together.

It is evident that the fringe F is susceptible of 35 being manufactured with the base cord 13 of any diametrical dimension desired, and this invention contemplates a condition under which the diameter of the base cord 13 will be substantially equal to the thickness of the braid 10.

40 While the fringe F is susceptible of being manufactured on various types of textile machinery, this invention has in mind the use of the well-known flat knitting machine, and a method of operation in which the fringe strands 14 are 45 simultaneously joined to a pair of base cords 13, and the strands later divided. In actual practice, a pair of the base cords 13 are fed to a flat knitting machine at the same time as is the strand which is later cut up into the various pieces making up the fringe.

The strand is referred to in Figure 5 by the reference character 18. The knitting machinery

is effective to cause the strand 18 to assume a loop formation extending between the base cords 13 with the bends 16 of the loop engaging and overlapping a portion of the respective base cords. One set of the knitting needles of the machine is 5 now effective to stitch the bends of the loops to the base cord by a stitching operation as is commonly carried out by this type knitting machine. After the bends of the various loops made up by the strand 18 have been stitched to the base cords 10 13, the strand 18 is cut along the medial line represented at 19 in Figure 5, to provide two separate fringes F.

In the embodiment of the invention herein illustrated and described, the base cord 13 is 15 shown as of a twisted construction, as the twisting operations are readily carried out in the textile art. The base cord 13 is shown as made up of three twisted yarns 20 which are in turn twisted together to make up the base cord. Obviously, the invention is not to be limited to these 20 particular details as various modifications thereof may be modified in putting the invention into practice, within the purview of the appended claims.

I claim:—

1. A rug comprising a main body portion formed from a braid wound about itself with the outer peripheral edge of the said body portion defined by the outermost turn of the braid, a 30 fringe consisting of a base cord having substantially the same diametrical dimension as the thickness of the braid making up the main body portion, and fringe strands knitted to the base cord, and means for attaching the base cord in 35 abutting relation to the outermost turn of the braid.

2. A rug comprising a main body portion formed from a braid wound about itself with the outer peripheral edge of the said body portion 40 defined by the outermost turn of the braid, interstitching joining adjacent turns of the braid together, a fringe consisting of a base cord having substantially the same diametrical dimension as the thickness of the braid making up the main 45 body portion, and fringe strands knitted to the base cord, the base cord being in abutting engagement with the outermost turn of the braid, and interstitching between said base cord and said outermost turn of the braid.

CLARENCE F. ARNOLD.
